US0D1014772S

(12) **United States Design Patent** (10) Patent No.: **US D1,014,772 S**
(45) Date of Patent: ** Feb. 13, 2024

(54) **VIBRATION MASSAGER**

(71) Applicant: **DONGGUAN JINDOYUN SILICONE ELECTRONICS CO., LTD.**, Dongguan (CN)

(72) Inventor: **Xuefei Cai**, Dongguan (CN)

(73) Assignee: **DONGGUAN JINDOYUN SILICONE ELECTRONICS CO., LTD.**, Dongguan (CN)

(**) Term: **15 Years**

(21) Appl. No.: **29/849,130**

(22) Filed: **Aug. 9, 2022**

(51) LOC (14) Cl. **24-01**

(52) U.S. Cl.

USPC **D24/215**

(58) **Field of Classification Search**

Primary Examiner — Michael A Maharajh

(57) **CLAIM**

The ornamental design for a vibration massager, as shown and described.

DESCRIPTION

FIG. 1 is a perspective view of a vibration massager showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the vibration massager that form no part of the claimed design.

1 Claim, 8 Drawing Sheets
